UNITED STATES PATENT OFFICE.

JOHN L. BRABYN, OF NEW YORK, N. Y.

LATH FOR BUILDINGS.

Specification of Letters Patent No. 17,550, dated June 16, 1857.

To all whom it may concern:

Be it known that I, JOHN L. BRABYN, of the city, county, and State of New York, have invented a new and useful Improvement 5 in Lathing the Walls and Ceilings of Buildings Preparatory to Plastering the Same, the use of which is calculated to lessen the expense of plastering both by the saving of labor and material; and I hereby declare 10 the following to be a full, clear, and exact description of my said improvement, reference being had to the drawings accompanying and making part of this specification.

My improvement consists in the manner 15 of preparing and applying the laths, and first in preparing them I form a groove or slot in one or both edges of the lath, by cutting out a certain portion of one side in the form of a half dovetail, or any other shape, 20 so that when combined with its fellow or when two grooved edges, or one grooved and one plain edge are placed together there shall be formed an interstice or groove in the form of a dovetail or its equivalent for 25 the purpose of holding the plastering material firmly to its place when crowded or pressed into the interstices so formed. That portion of the lath which remains of full width which will always form the back side 30 when properly laid, will constitute a solid support for the mortar, thus preventing it from pressing through between the laths, as is always the case where the interstices are formed by laying the lath with a space be- 35 tween them, and allowing the mortar to form a clench behind the laths. In the im- proved method above described, the clench is formed by the groove in the lath being widest at the back, and this groove and the 40 solid support for the mortar are both formed by or in the laths and entirely independent of the wall or ceiling to which they are fas- tened, the laths being laid with close joints at the back instead of a certain distance 45 apart as in the old method. By this ar- rangement it will be readily perceived that although the lathing may be furred off as it is termed, yet no extra quantity of mortar will be required, as the mortar does not press 50 through and fall down behind the wall, but simply fills up the grooves provided in the lathing.

Another advantage will readily be per- 55 ceived, that even where the laths are applied directly upon a brick wall without being furred off, which is often the case, the solid

back of wood, formed by the peculiar con- struction and application of the laths, will prevent in a great measure the dampness of the brick wall from communicating with the 60 plastering as the wood is not so good a con- ductor of moisture as the mortar itself would be.

In frame buildings a very great advantage 65 is derived from the use of this improvement as the lathing forms a tight ceiling of itself, thus contributing largely to the warmth of the interior of the buildings. The founda- tion of the wall being much more substan- tial, there is less liability of the walls crack- 70 ing, and the weight of the plastering being much reduced there is consequently less lia- bility of its falling off. This is of particular advantage in overhead walls, as it is fre- quently the case that large quantities of the 75 wall come down, simply from its own weight when put on in the old method.

Another advantage is derived from the in- creased facility of laying the laths, as no 80 regard is to be had to the spaces between them, the edges being placed tight together, and the interstices formed with mechanical exactness. The wall will be much more solid and firm, as the mortar can be pressed upon the lathing with any degree of force 85 that may be desired, which is not the case in the old method, as the harder it is pressed the more it is forced through between the laths and wasted behind them.

The grooves are indicated in the drawing 90 by the letters (a a) and the back support by the letters b b.

What I claim as my invention, and desire to secure by Letters Patent, is—

The forming of the interstices in the form 95 of a dovetail or its equivalent and the back support for the mortar in the laths them- selves, and entirely independent of anything that may be placed behind them, by groov- ing one or both edges of the lath on end side 100 and leaving the other side the full width, so that when the same are in place their edges shall join at the back side to prevent the plastering material from pressing through between the laths, the grooves form- 105 ing the clenches to hold the mortar firmly in place, substantially as set forth.
